UNITED STATES PATENT OFFICE.

DAVID McCANCE, OF LOCKPORT, NEW YORK.

POLISHING-MACHINE.

No. 823,540.

Specification of Letters Patent.

Patented June 19, 1906.

Application filed June 28, 1905. Serial No. 267,434.

To all whom it may concern:

Be it known that I, DAVID McCANCE, a citizen of the United States, residing at Lockport, in the county of Niagara and State of 5 New York, have invented a new and useful Polishing-Machine, of which the following is a specification.

This invention relates to polishing-machines, and has for its principal object to provide a novel form of mechanism for the polishing of small articles—such, for instance, as those employed as trimmings in the manufacture of metallic bedsteads, chandeliers, and other objects of generally cylindrical 15 form.

A further object of the invention is to provide a novel form of machine in which the articles to be polished are carried by a revolute chuck, which may be reciprocated in the 20 direction of its length in order to present all portions of the surface to the action of a revolute polishing-wheel.

A still further object of the invention is to provide a mechanism of simple construction 25 for effecting the reciprocatory movement of the chuck and to provide for the ready opening and closing of said chuck, so that the articles may be quickly placed in position and removed.

With these and other objects in view, as will more fully hereinafter appear, the invention consists in certain novel features of construction and arrangement of parts hereinafter fully described, illustrated in the accompanying drawings, and particularly pointed 35 out in the appended claims, it being understood that various changes in the form, proportions, size, and minor details of the structure may be made without departing from 40 the spirit or sacrificing any of the advantages of the invention.

In the accompanying drawings, Figure 1 is a front elevation of a polishing-machine constructed in accordance with the invention. 45 Fig. 2 is a side elevation of the same. Fig. 3 is a detail view, on a larger scale, of a portion of the chuck. Fig. 4 is a transverse section on the line 4 4 of Fig. 1, showing the chuck-carrying spindle and its hollow driving-shaft.

Similar numerals of reference are employed 50 to indicate corresponding parts throughout the several figures of the drawings.

The polishing-wheel 10 may be of any suitable construction and operated in any suitable manner, the wheel in the present instance being mounted on a short shaft 11, that is ar-

ranged at the forward end of a frame 12, the rear end of which is pivoted on a shaft 13, connected by a suitable belt and pulleys to the shaft 11. The front end of the pivot-frame is supported by a spring 14, and a toggle-lever connection 15 is utilized as a means for forcing the frame and the wheel downward in the direction of the work. This portion of the mechanism, however, constitutes 60 no part of the present invention, and the polishing-wheel may be mounted in any suitable manner.

At a point adjacent to the front end of the pivot-frame is a stationary frame including 70 standards 17 and a bed-plate 18, the latter being provided with vertical brackets or standards 19, having bearings 20 for the reception of a hollow shaft 21, on which is mounted a pulley 22, that is connected by a 75 belt 23 to a driving-pulley 24 on a line-shaft 25.

Extending through the hollow shaft 21 is a longitudinally-movable spindle that is feathered to the shaft, so that it may slide freely to and fro within the same, and at one end of 80 the spindle is a chuck 27 for the reception of the work. The opposite end of the spindle is reduced in diameter and receives a sleeve 28, formed at one end of a pin 29, said pin being carried by lever 30, that is fulcrumed at one 85 end to fixed bracket 31 and is provided at its opposite end with an operating-handle 32, the handle being disposed within convenient reach of the operator, so that by manipulating the same the spindle may be moved to and 90 fro and the work moved transversely of the polishing-wheel, thus presenting all portions of the work to the wheel.

The chuck is formed of two members, each of which is provided with a threaded collar 32', 95 and said collars are grooved for the reception of pins or antifriction-rollers extending from the bifurcated ends of a pair of levers 33 and 34, one of these levers being hung on a bracket 35, depending from the sleeve or other suitable point of support, while the arm 33 is connected to the lever 34 by a short arm 35', and the two levers are connected to each other at a point below this arm by means of a helical tension-spring 37, that tends to 100 draw the levers toward each other.

The two levers 33 and 34 are provided with antifriction-rollers 38, that bear against the opposite faces of a double cam 39, that is carried by a pin 40, and to the pin is secured an operating-handle 41, by which said cam may 105 be turned for the purpose of spreading the

levers, and thus spreading the members of the chuck and causing the latter to engage with the article to be polished. When the lever is turned in the opposite direction, the 5 spring 37 will draw the two grooved collars toward each other, and the members of the chuck will hold the work.

In operation the handle 41 is turned in order to open the chuck for the reception of the article to be polished, and on turning the handle in the opposite direction the chuck members are spread and engage with the work. The polishing-wheel and the chuck-carrying spindle being then rotated, the operator may 15 grasp the handle 43 of the polishing-wheel-adjusting device in the left hand and the handle 32 of the chuck-adjusting device in the opposite hand, and by manipulating both the article may be thoroughly and perfectly polished.

Having thus described the invention, what is claimed is—

1. The combination with a polishing-wheel, of a chuck, a spindle carrying said chuck, means for revolving the spindle, and 25 means for reciprocating said spindle in a direction parallel with the axis of the polishing-wheel, whereby the work carried by the chuck may be moved transversely across the periphery of said polishing-wheel.

30 2. In a polishing-machine, the combination with a polishing member, of a chuck formed of a plurality of sections, a pair of grooved

sleeves independently connected to said sections, a pair of levers having bifurcated end portions provided with pins entering said grooved sleeves, a spring tending to draw the levers toward each other, and a revolute cam for separating said levers. 35

3. In a device of the class specified, the combination with a polishing member, of a frame, a hollow shaft having bearings in said frame, a spindle extending through such hollow shaft, and feathered thereto, said spindle having a reduced portion at one end, a collar fitting on the reduced end portion of the 45 spindle, a pin projecting from the collar, a lever fulcrumed to the frame and carrying said pin, a two-part chuck arranged at the opposite end of the spindle, grooved collars connected to the chuck members, and a pair of 50 levers having bifurcated end portions provided with pins entering said grooved collars, a spring tending to draw the levers toward each other, and a revolute cam arranged between the two levers and designed to separate the same and open the chuck.

In testimony that I claim the foregoing as my own I have hereto affixed my signature in the presence of two witnesses.

DAVID McCANCE.
